UNITED STATES PATENT OFFICE.

LEWIS CONDICT BAYLES, OF JOHANNESBURG, TRANSVAAL.

ROCK-DRILLING-MACHINE CHUCK.

No. 903,948.

Specification of Letters Patent.

Patented Nov. 17, 1908.

Application filed July 9, 1907. Serial No. 382,962.

To all whom it may concern:

Be it known that I, LEWIS CONDICT BAYLES, a citizen of the United States, and resident of Johannesburg, Transvaal, have 5 invented certain new and useful Improvements in Rock-Drilling-Machine Chucks, of which the following is a specification.

This invention relates to the chucks of rock-drilling machines, and in particular to 10 that type in which the drill steel or bit is secured in the head by means of a wedge and gripping pad in conjunction with a **U** bolt. With this type of chuck as at present constructed difficulty is frequently experienced 15 in inserting the shank end of the steel in renewing the bits, owing to the gripping pad and wedge falling into the bore of the chuck when the bit is removed, consequently necessitating the partial rotation of the chuck to 20 allow the pad to fall sufficiently out of the bore to permit of the insertion of the steel.

One object of my invention is to obviate this defect. The gripping pad and wedge have heretofore had a tendency to disengage 25 the **U** bolt and fall out of position and another object of my invention is to prevent such disengagement.

A further object is to insure the maintenance of the wedge parallel with the bore 30 of the chuck or axis of the piston rod.

Another defect of the type of chuck referred to has been that the driving forward of the wedge to secure the bit has forced the forward end of the gripping pad against the 35 front end of the pad slot in the chuck. As the chuck head is necessarily made of comparatively soft metal the result has been a distortion of the front head or the gradual hammering outward of the metal of the head 40 at the front end of the slot.

My invention also relates to the construction and arrangement of a half bushing for the chuck. Heretofore the head of the chuck has been constructed with one or more holes 45 or recesses in the bottom to be engaged by a projection or projections formed on the outside of the half bushing. Now this construction has weakened the head and increased the tendency for it to spread or burst when the 50 wedge draws up the **U** bolt in the operation of securing the bit.

To the attainment of these several objects my invention consists, firstly, in flaring or making bell mouthed the longitudinal groove 55 or recess in the gripping pad which bears

on the bit shank, (I prefer to make it flaring at both ends to permit of the reversal of the gripping pad) and to the provision of longitudinal ribs or projections on the gripping pad which are adapted to engage the top of the head and so prevent the pad falling beyond a certain distance into the bore of the chuck when the drill is removed. Secondly, to the provision on the top of the gripping pad of a rib or projection and a correspondingly shaped longitudinal recess or groove in the contiguous face of the wedge (or vice versa). Thirdly, to the provision of recesses in the longitudinal ribs or projections on the gripping pad to engage the inside of the **U** bolt to prevent longitudinal movement of the pad. Fourthly, to the provision of two parallel grooves or recesses formed longitudinally of and in the bore of the head and in providing on the half bushing two corresponding parallel ribs or projections engaging said groove (or vice versa), and fifthly, to the provision in the sides of the half bushing of recesses or grooves which are engaged by the **U** bolt and operate to prevent longitudinal displacement of the half bushing.

By the present improvements it is not possible to remove any part of the chuck or for any part to get out of alignment or position except both nuts of the **U** bolt be first removed and the **U** bolt withdrawn.

To facilitate the detailed description of the several improvements I append four sheets of illustrative drawings numbered to correspond with the following description 90 thereof.

Figure 1 is an end elevation of the chuck. Fig. 2 is a longitudinal section of the head showing the gripping pad and wedge in elevation. Fig. 3 is a front elevation of the gripping pad detached. Fig. 4 is a side elevation of Fig. 3. Fig. 5 is a plan of Fig. 4. Fig. 6 is a side elevation of the wedge. Fig. 7 is a plan of Fig. 6. Fig. 8 is a section of Fig. 7 on line *x*—*x*. Fig. 9 is an end elevation of the half bushing, and Fig. 10 is a plan of Fig. 9. Fig. 11 is a side elevation of Fig. 10. Fig. 12 is an end elevation of a chuck illustrating certain modifications. Fig. 13 is a longitudinal section, with the 105 pad and wedge in elevation, of the chuck shown in Fig. 12. Fig. 14 is an end elevation of the gripping pad detached. Fig. 15 is a side elevation of Fig. 14. Fig. 16 is a plan of Fig. 15. Fig. 17 is a side 110

elevation of the wedge. Fig. 18 is a plan of Fig. 17. Fig. 19 is a section of Fig. 17 on line $y-y$. Fig. 20 is an end elevation of the half bushing. Fig. 21 is a plan of Fig. 20, 5 and Fig. 22 is a side elevation of Fig. 21.

Referring to the arrangement illustrated in Figs. 1 to 11, illustrative of certain features of the invention, 1 is the head or body of the chuck fixed to or formed integral with 10 the piston rod 2.

3 is the bore of the chuck in which is secured the shank of the bit or drill steel 4. The drill steel is shown of the ordinary octagonal section but it will be obvious that by 15 suitably shaping the half bushing and gripping pad internally it may be made of any other desired section. The shape shown may in some cases be preferred as it obviates the necessity for shanking or rounding the end 20 of the drill steel 4.

5 is the **U** bolt, which, as usual, passes through holes 6 formed through the head 1 and has screwed on its extremities the retaining nuts 7.

25 8 is a longitudinal slot formed through the head 1 communicating with the bore 3, and 9 is the gripping pad positioned therein. The gripping pad 9 as shown, is formed on the inside with an angular recess or groove 30 10 to receive a portion of the drill steel 4. The ends of this groove or recess 10 are made with a flaring mouth or made bell shaped as seen at 11 in Figs. 2, 3 and 4. This configuration of the ends of the gripping pad 35 9 facilitates the insertion of the drill steel 4 by increasing the size of the opening between the end of the pad and the bushing. In the drawing I show both ends of the pad 9 shaped as described in order to permit of 40 the pad being reversed if desired. The pad 9 is also fashioned with two parallel longitudinal ribs or projections 12 at the outside, which engage the top of the head 1 along the top edges of the longitudinal slot 8 and so 45 operate to prevent the gripping pad 9 falling into the bore of the chuck beyond a certain point. If desired, these ribs or projections 12 on the gripping pad 9 may be dispensed with and the gripping pad be allowed to 50 fall sufficiently far into the bore 3 of the chuck for the lower edges 13 to engage the upper edges 14 of the half bushing 15. In the ribs or projections 12 are formed curved recesses 12^a which are engaged by the inside 55 of the **U** bolt 5 and so prevent longitudinal movement of the pad 9 in the slot 8, which obviates the front end of the pad striking the front end of the slot when the wedge is driven forward.

60 17 is the wedge, the plain face of which, when the wedge is in position has contact with the top of the pad 9, so that the wedge and pad slidingly engage each other. The upper or inclined tapered face 19 of the 65 wedge is rounded transversely—see Figs. 1

and 8—to correspond to the curvature of the **U** bolt 5 which it slidingly engages. This construction operates to retain and guide the wedge when it is driven in either direction and insures it being maintained parallel to the bore 3 of the chuck or longitudinal axis of the drill steel 4. 70

20 are lugs or projections on the ends of the wedge 17 to assist in preventing it disengaging the **U** bolt 5 and for receiving the 75 impacts of a hammer for driving the wedge in either direction.

The half bushing 15 is constructed along each edge on the outside with projections 21 and in the bore of the chuck are formed correspondingly shaped grooves or recesses 22 engaged thereby. This secures the half bushing 15 against rotary movement in the bore 3 of the chuck. The half bushing 15 is shown recessed longitudinally at 23 80 85 to receive a portion of the drill steel 4. The bolt holes 6 intersect the longitudinal grooves or recesses 22 in the bore of the chuck and in the sides or upper edges 14 of the half bushing 15 are formed recesses 24 90 which are engaged by the bolt 5 and serve to prevent longitudinal displacement of the half bushing 15.

The construction described in connection with Figs. 1 to 11 is that preferred for new 95 chucks.

Referring now to the construction illustrate in Figs. 12 to 22, I illustrate the application of certain features of the invention to a standard type of rock-drill chuck. The 100 same numerals of reference indicate the same or corresponding parts in these figures of the drawings. In this construction, on the top of the gripping pad 9 and longitudinally thereof is provided a rib or projection 16. 105 The wedge 17 on its inner parallel edge is constructed with a longitudinal groove or recess 18 in which the projection 16 on the pad 9 fits, so that the wedge and pad slidingly engage each other. This construction 110 serves as a retaining and guiding means for the wedge 17 and insures it being maintained parallel to the longitudinal axis of the bore 3 of the chuck or drill steel 4. The upper inclined or tapered edge 19 of the 115 wedge 17 slidingly engages the inside of the **U** bolt 5.

It will be apparent that instead of forming the projection 16 on the pad 9 and the recess 18 on the wedge 17, the recess may 120 be formed in the pad and the projection on the wedge.

The recesses 24 in the half bushing 15, with which the **U** bolt 5 engages, are made sufficiently long to provide for the reversal 125 of said bushing, as the **U** bolt is not in this case positioned at the center of the longitudinal ribs or projections 21 as in the previously described construction. When in position the **U** bolt 5 engages the same end 130

of each of the recesses 24 and when the half bushing is reversed it engages the opposite end of each of the recesses 24.

What I claim as my invention and desire

5 to protect by Letter Patent is:—

1. In a rock-drilling machine chuck the combination of the head and **U** bolt with a half bushing positioned in the bore of the head and non-rotatably retained therein by 10 longitudinal projections engaging corresponding longitudinal grooves, as set forth.

2. In a rock-drilling machine chuck the combination of the head, **U** bolt, and gripping pad, with a half bushing positioned in 15 the bore opposite the pad and non-rotatably retained therein by providing the head with longitudinal grooves and the half bushing with longitudinal projections engaging said grooves, as and for the purpose set forth.

20 3. In a rock-drilling machine chuck, the combination of the head, **U** bolt, and gripping pad, with a half bushing arranged in the bore opposite the pad the half bushing being formed with external longitudinal 25 projections engaging corresponding longitudinal recesses in the bore, and means for locking the half bushing in the bore by the **U** bolt as set forth.

4. In a rock-drilling machine chuck, the 30 combination of the head, **U** bolt and a gripping pad locked in position by the **U** bolt, with a half bushing arranged in the bore opposite the pad, the half bushing being formed with external longitudinal projections 35 engaging corresponding longitudinal recesses in the bore, said external projections having recesses registering with the bolt holes in the head so that the half bushing is engaged by the **U** bolt and thereby secured 40 against longitudinal displacement, as set forth.

5. In a rock-drilling machine chuck, in combination, a head constructed with an axial bore, a longitudinal slot in communication 45 with the bore, a transverse bolt hole at each side of the bore, and oppositely disposed longitudinal recesses in the bore intersecting the bolt holes, a **U** bolt located in the bolt holes, a pad in the slot, said pad being constructed along its longitudinal edges with outwardly extending projections, overlapping the longitudinal edges of the slot, each of said projections having a recess engaged 50 by the **U** bolt, a wedge arranged between the **U** bolt and pad, a half bushing constructed 55 along its two longitudinal edges with external projections engaging the oppositely disposed longitudinal recesses in the bore,

said external projections having recesses coinciding with the bolt holes and through which latter recesses the **U** bolt passes, as set forth.

6. In a rock-drilling machine chuck, the combination of a head, having a slot communicating with the bore thereof, a gripping pad located in said slot, and a wedge positioned next the pad, the pad and wedge being formed, the one with a projection and the other with a groove in which said projection engages, as and for the purpose set forth. 70

7. In a rock-drilling machine chuck, in combination, a head constructed with an axial bore, a longitudinal slot in communication with the bore, and a transverse bolt hole at each side of the bore, a **U** bolt in the bolt 75 holes, a pad in the slot, said pad being constructed along two edges with outwardly extending projections overlapping the longitudinal edges of the slot, each of said projections having a recess engaged by the **U** bolt 80 and a wedge positioned between the **U** bolt and pad, the pad and wedge being formed, the one with a projection and the other with a groove in which said projection engages, as and for the purpose set forth. 85

8. In a rock-drilling machine chuck, in combination, a head constructed with an axial bore, a longitudinal slot in communication with the bore, a transverse bolt hole at each side of the bore, and oppositely disposed longitudinal recesses in the bore intersecting the bolt holes, a **U** bolt located in the bolt holes, a pad in the slot, said pad being constructed along its longitudinal edges with outwardly extending projections, 95 overlapping the longitudinal edges of the slot, each of said projections having a recess engaged by the **U** bolt, a wedge arranged between the **U** bolt and pad, the pad and wedge being formed, the one with a projection and the other with a groove engaged thereby, a half bushing constructed along its two longitudinal edges with external projections engaging the oppositely disposed longitudinal recesses in the bore, said external projections having recesses coinciding with the bolt holes and through which latter recesses the **U** bolt passes, as set forth. 100 105

In witness whereof I have hereunto set my hand in the presence of two subscribing 110 witnesses.
